UNITED STATES PATENT OFFICE.

FREDERICK HYMANS, OF YONKERS, NEW YORK, ASSIGNOR TO OTIS ELEVATOR COMPANY, OF JERSEY CITY, NEW JERSEY, A CORPORATION OF NEW JERSEY.

ELEVATOR SAFETY APPLIANCE.

Application filed August 17, 1926. Serial No. 129,777.

The invention relates to safety appliances and particularly to safety appliances for elevators.

In elevator operation, it sometimes happens that, owing to faulty operation or other reason, the elevator car runs past a terminal landing. If the car is descending under such circumstances it may be brought to rest by a buffer placed in the bottom of the hatchway, but its counterweight at this time is ascending and this counterweight, being unrestrained by any force other than its own weight, may run into the overhead work before coming to rest, thus resulting in damage to the elevator apparatus. If the car is ascending under such circumstances it may strike the overhead work causing injury to the elevator apparatus and possible harm to passengers. This liability of damage is augmented in high rise elevators, where, with the car passing the upper terminal landing, there is a long line of descending hoisting ropes pulling down on the counterweight side of the hoisting drum and urging the car upwardly. At this time there is but a short line of hoisting ropes on the car side of the hoisting drum and these ropes are moving upwardly. Taking the moving system as a whole, the weight of the counterweight hoisting ropes, their kinetic energy, the kinetic energy of the car and that of the hoisting ropes above the car, constitute factors urging the car upwardly whereas the factors opposing this motion may be merely the weight of the car together with that of the hoisting ropes above the car. Furthermore, in systems where a traction drive is employed, in the event that the elevator motor continues to operate, the tractive effort of the hoisting drum will be transmitted to the hoisting ropes owing to the stress in the hoisting ropes at each side of the drum. This will also tend to cause the car to continue in its upward movement.

The principal object of this invention, therefore, is to prevent under the above circumstances the downwardly moving hoisting ropes from assisting in the movement of the upwardly moving body, whether this body be the car or the counterweight.

One feature of the invention is the provision of a safety appliance which operates to grip the hoisting ropes when the counterweight descends below a predetermined point.

Another feature of the invention is the provision of a safety appliance which operates to grip the hoisting ropes when the car descends below a predetermined point.

Still another feature is the provision of a safety appliance of the above character which is of simple construction and reliable in operation.

Other features and advantages will become apparent from the specification, taken in connection with the accompanying drawings wherein one embodiment of the invention is illustrated.

In the drawings:

Figure 1 is a schematic representation of a typical elevator system illustrating the adaptation of the safety appliance to both the car and the counterweight;

Figure 2 is a plan view of a rope clamp taken along the line 2—2 of Figure 1;

Figure 3 is a view in partial section taken along line 3—3 of Figure 2;

Figure 4 is an end view of Figure 3 shown in half section along the line 4—4 of Figure 3;

Figure 5 is a wiring diagram illustrating the manner in which the safety appliances may cooperate with an elevator control system, and

Figure 6 is a fragmental representation of an arrangement similar to Figure 1 but with the operating levers at the top of the elevator hatchway.

Referring to Figure 1, the hoisting ropes 3, only one rope being seen in this figure, pass over the hoisting drum 4 and connect the car 1 to the counterweight 2. The motor 5 drives the drum 4 through suitable gearing mounted in the housing 6, thus effecting the raising and lowering of the car and counterweight. An electromagnetic brake 7 is applied to the motor shaft between the motor and the gear housing 6 for the purpose of bringing the motor, and therefore the car and counterweight to a stop. Compensating ropes 8, connected at one end to the car 1, pass under the compensating sheave 10 and at their other

end are connected to the counterweight 2. The car buffer is designated 11, while the counterweight buffer is designated 12. The upper limit switch 9 and the lower limit switch 19 positioned in the hatchway are arranged to be actuated upon overtravel of the car by a cam 149 carried by the car. The contacts 169 of limit switch 9 and contacts 170 of limit switch 19 remain in engagement except when held separated by the cam 149. The car and counterweight guide rails are not shown for convenience of illustration.

According to the preferred arrangement, a cam 13 is secured to the counterweight 2. A lever 14 is pivotally mounted, as on the shaft 18, near the bottom of the hatchway and carries a roller 15 on one arm thereof. The roller 15 is positioned to be engaged by the cam 13. The remaining arm of lever 14 extends upwardly and is formed with a catch 16 at its upper end. Catch 16 extends over an abutment 17 secured to the lower end of a lever 20. Lever 20 is fulcrumed on the shaft 21 positioned in the hatchway. A rope 22 has its lower end attached to the lever 20 by the yoke 23 and pin 24. The upper portion of this rope extends over sheaves 139 and 149 positioned in the hatchway and is similarly attached to a lever 25 of a rope clamp 26. The rope clamp 26 is arranged near the top of the elevator hatchway, being supported as on the I-beams 27 and secured thereto by clips 159. This rope clamp is arranged to grip the hoisting ropes, leading from the drum 4 to the counterweight, at a point near the drum 4.

The construction of the rope clamp 26 is illustrated in Figures 2, 3 and 4. This clamp comprises a housing 28 having two spaced end parts 29 and 30 connected by two side plates 31 and 32. The end parts are of similar construction and each consists of a top and bottom portion connected by a central portion. The central portions are formed with grooves 33 and 34 at their sides. The side plates 31 and 32 are of the same construction and have tongues 35 and 36 fitting in the grooves 33 and 34 of the end parts. Screws 39 extend through the side plates and are threaded into the end parts and serve to hold the end parts and the side plates constituting the housing 28 together.

Lever 25, at a point intermediate its ends, is pivotally mounted on a shaft 37. Shaft 37 extends through lugs 38 and 40 formed on the top of end part 30 of the rope clamp housing and is retained in place as by cotter pins. The arm of the lever 25, to which the rope 22 is attached, carries two contacts for cooperating with two fixed contacts, these pairs of cooperating contacts being designated 41 and 42. The other arm of the lever 25 is widened for the greater part of its length and is formed with an opening 43, the sides of the opening being designated 44 and 45. The ends of these sides that are farther

from the pivotal shaft 37 are joined by a yoke 46. A weight 47 straddles the yoke 46, being retained thereon by a set screw 48. Side 44 is formed with a bearing 50, having a bearing cap 51. Bearing cap 51 is secured to side 44 by screws 52. Side 45 is also formed with a bearing 53, having a bearing cap 54 secured to that side by screws 55. Adjacent the side 44 and within the opening 43 there is positioned an equalizing-bar capable of swinging in a vertical plane. This equalizing-bar has a pivotal stud projecting outwardly from its central portion and extending through the bearing 50. Circular apertures 58 and 60 are provided near the ends of the equalizing-bar 56. Adjacent the side 45 and within the opening 43 there is also positioned an equalizing-bar 61 capable of swinging in a vertical plane. This equalizing-bar has a pivotal stud 62 projecting outwardly from its central portion and extending through the bearing 53. Circular apertures 63 and 64 are provided near the ends of the equalizing-bar 61. A cross-bar 65 is positioned within the opening 43 and has cylindrical end portions extending through apertures 58 and 63 of equalizing-bars 56 and 61. Cross-bar 65 is retained in position with respect to the equalizing-bars by the use of cotter pins positioned at the extremities of the cylindrical end portions. This cross-bar is of rectangular cross-section except for those portions where it extends through the equalizing-bars and is provided with an aperture 66 midway of its length. A yoke 67 is pivotally connected to the cross-bar 65 by means of a pin 68 extending through the aperture 66 and the bifurcated end of the yoke. A cotter pin extends through pin 68 at each side of the yoke thereby retaining this pin in place. The lower end of the yoke 67 is formed into a tongue 70. Tongue 70 fits within the forked end of a stud 71 and is pivotally connected therewith by means of a pin 72. The lower portion of the stud is threaded into a wedge 73 positioned within the clamp housing 28.

A cross-bar 75, of the same construction as the cross-bar 65, also is positioned within the opening 43 and has cylindrical end portions extending through apertures 60 and 64 of the equalizing-bars. Cross-bar 75 is likewise connected at its midpoint to a yoke 76. Yoke 76 is pivotally connected to the forked end of a stud 77. The lower end of the stud 77 is threaded into a wedge 78 positioned within the clamp housing 28. The equalizing-bars 56 and 61 together with the cross-bars 65 and 75 form a rectangular frame 81 pivotally mounted on the sides 44 and 45 of the lever 25. The hoisting ropes 3 pass through the opening within frame 81, between wedges 73 and 78 and through an opening 84 in the bottom of the rope clamp housing. Wedge 73 is formed with a vertically extending cylindrical recess 74. Within

this recess a clamp 69 is retained as by means of a dove-tailed connection 89 between the wedge and clamp. Clamp 69 may swivel within recess 74 about a vertical axis extending midway between wedges 73 and 78. The gripping face 82 of the clamp 69 is formed with grooves 85 and 86 that are concentric with and extend parallel to the hoisting ropes. Wedge 78 is of the same construction as wedge 73. The clamp 80 within wedge 78, as in the case of clamp 69, is free to swivel about a vertical axis extending midway between wedges 73 and 78. Likewise the gripping face 83 of the clamp 80 is formed with grooves 87 and 88 that are concentric with and extend parallel to the hoisting ropes. The inclined face of the wedge 73 is designated 90. This face engages the inclined face 91 of a wedge 92. Wedge 92 rests on the bottom portion of end part 29 of the rope clamp housing. Wedge 92 has a stud 79 projecting therefrom. This stud extends through the central portion of end part 29 and has a nut 157 and a lock nut 158 threaded on the end thereof. A compression spring 93 surrounds the stud 79 and extends between the wedge 92 and the central portion of the end part 29 of the housing. The inclined face of the wedge 78 is designated 94. This face engages the inclined face 95 of a wedge 96. Wedge 96 is of the same construction as the wedge 92 and rests on the bottom portion of end part 30 of the rope clamp housing. The stud 99 projecting from wedge 96 has a nut 160 and a lock nut 161 on the end thereof. A compression spring 97 is likewise interposed between the wedge 96 and the central portion of the end part 30.

The rope clamp as illustrated in Figure 1 is in its normal and disengaged position. In this position the lever 20, acting through rope 22 and lever 25 of the rope clamp, causes the pairs of cooperating contacts 41 and 42 to be in engagement. In such position the weight 47 is retained in an elevated position and the clamps 69 and 80 carried by wedges 73 and 78 do not engage the hoisting ropes.

A cam 98 is secured to the car 1. A lever 100 is pivotally mounted, as on the shaft 101, near the bottom of the hatchway and carries a roller 102 on one arm thereof. The roller 102 is positioned to be engaged by the cam 98.

The remaining arm of the lever 100 extends upwardly and is formed with a catch 103 at its upper end. Catch 103 extends over an abutment 104 secured to the lower end of a lever 105. Lever 105 is fulcrumed on the shaft 106 positioned in the hatchway. A rope 107 has its lower end attached to the lever 105 by the yoke 108 and pin 110. The upper portion of the rope 107 extends over sheaves 109 and 111 positioned in the hatchway and is attached to a lever 112 of a rope clamp 113. Lever 112 carries two contacts for cooperating with two fixed contacts, these pairs of cooperating contacts being designated 115 and 116. Rope clamp 113 is arranged near the top of the elevator hatchway, being supported on I-beams 114 and secured thereto by clips 119. This rope clamp is arranged to grip the hoisting ropes, leading from the drum 4 to the car, at a point near the drum 4. Rope clamp 113 is of the same construction as rope clamp 26 and therefore would appear to require no further explanation.

Referring to the wiring diagram of Figure 5, no attempt is made to show the coils and contacts of the various electromagnetic switches in their associated positions, a "straight" diagram being employed wherein the coils and contacts of the various switches are separated in such manner as to render the circuits involved relatively simple. Also the parts of other switches and apparatus are separated in the interest of simplifying the diagram. For a clearer understanding of the invention, the stationary contacts of the switches are illustrated in cross section. It is to be understood that the control system illustrated is chosen merely for convenience of description.

The diagram shows a system comprising an elevator motor 5 and a car switch designated as a whole by the numeral 117 for controlling the operation of the motor. The motor 5 comprises the armature 118, series field winding 120, and the separately excited field winding 121. Stopping resistance 122 is provided for the motor armature 118. The release coil for the elevator motor electromagnetic brake 7 (see Figure 1) is designated 123. A double pole knife switch 124 is used for connecting the system to the supply mains 125 and 126. In order to suit the type of diagram employed, the blades of this switch are shown separated. 127 is the safety switch in the car. Discharge resistances for the elevator motor field windings, and for the electromagnetic brake, together with the various door and gate contacts have been omitted to simplify the description.

The electromagnetic switches have been designated as follows:

- A—potential switch,
- B—up direction switch,
- C—down direction switch.

Throughout the description which follows, these letters, in addition to reference numerals, will be applied to the parts of the above enumerated switches. For example, contacts B 145 are contacts on the up direction switch, while actuating coil A 128 is the coil that operates the potential switch. The electromagnetic switches are shown in their deenergized positions.

Upon the closing of knife switch 124 the potential switch actuating coil A 128 is en-

ergized, the circuit for such coil being from the left-hand blade of switch 124, line 138, by way of line 130 through safety switch 127 in the car, by way of line 131 through contacts 169 of limit switch 9, through contacts 41 and 115 of the safety appliances, through coil A 128, through the other contacts 42 and 116 of the safety appliances and through contacts 170 of limit switch 19. The potential switch, upon operation, causes the engagement of contacts A 132 and A 133 preparing the circuits for the motor and the electromagnetic brake release coil. The condition of the circuits so far described might be termed 15 normal.

The operation of the system is as follows: Assume that the car is at rest at a lower terminal landing 59 (see Figure 1). In this position of the car the cam 98 carried by 20 the car is above the roller 102 and does not engage this roller. In order to start the car in the up direction, the operator moves the car switch into the position where its contact segment 134 bridges contacts 135 and 25 136. Upon the contact segment engaging contact 136, a circuit is completed for the actuating coil B 137 of the up direction switch. This circuit may be traced from the left-hand blade of switch 124, by way of line 30 138 and line 130, through safety switch 127, contacts 135 and 136 of the car switch, by way of line 140, through contacts C 141 and coil B 137, by way of line 142 to the right-hand blade of switch 124. Upon operation of the 35 up direction switch in response to the energization of its actuating coil B 137, contacts B 143 and B 144 separate and contacts B 145, B 146 and B 147 engage. The separation of contacts B 143 breaks the circuit leading from the car switch down feed contacts 148, contacts B 143 and the corresponding down direction switch contacts C 141 serving as electrical interlocks. The separation of contacts B 144 and the engagement of contacts B 145 and B 146 completes a circuit for the motor 40 armature. This circuit may be traced from the left-hand blade of switch 124, by way of line 138 through contacts A 132, by way of line 150 through contacts B 145 and contacts C 151, by way of line 152 through armature 118, back to line 138 through contacts B 146 and series field winding 120, by way of line 142 through contacts A 133, to the right-hand blade of switch 124. Starting 45 resistance and the accelerating switch for the motor armature have been omitted to simplify the description. The engagement of contacts B 145 also completes a circuit for the brake release coil 128. This circuit may be traced from the left-hand blade of switch 124, by way of line 138 through contacts A 132, by way of line 150 through contacts B 145, by way of line 154 through a portion of the stopping resistance 122, by way of line 50 155 through brake release coil 128, by way

of line 142 through contacts A 133, to the right-hand blade of switch 124. The engagement of contacts B 147 completes a circuit for the separately excited field winding 121. This circuit may be traced from the left-hand blade of switch 124, by way of line 138 through contacts A 132, by way of line 150 through contacts B 145, by way of line 154 through a portion of the resistance 122, by way of line 155 through contacts B 147 by 55 way of line 156 through winding 121, by way of line 142 through contacts A 133 to the right-hand blade of switch 124.

The brake release coil 128 being energized and current being supplied to the elevator 80 motor armature and field windings, the elevator motor starts, causing the car to ascend.

Assume that the car approaches the upper terminal landing 129 (see Figure 1) and the operator centers the car switch in order to 85 stop. The disengagement of contact 136 and contact segment 134 breaks the circuit for the actuating coil B 137 thus permitting the direction switch to drop out to break the circuit for the motor armature and field windings and to cause the application of the brake 90 7 to stop the car. With the car at the upper terminal landing the counterweight cam 13 is above the roller 15 carried by the lever 14 and does not engage this roller. 95

Under certain conditions of operation as for example should the operator fail to center the car switch and should the limit switches fail to function the car may run past the upper terminal landing to the extent of 100 causing the cam 13 to strike the roller 15. Roller 15 then rides outwardly along the inclined surface of the cam. This outward movement of the roller 15 causes lever 14 to swing about its pivotal shaft 18 in a counterclockwise direction as viewed in Figure 1. Should the downward movement of the counterweight be above a predetermined amount, the roller 15 will move outwardly to the extent of causing the catch 16 on lever 14 to 105 disengage the abutment 17 on the lower end of lever 20. Lever 20 is now free to swing upwardly, releasing the tension in rope 22. Weight 47 is thus permitted to fall turning lever 25 about its pivotal shaft 37. The turning of lever 25 at first causes the separation of the pairs of cooperating contacts 41 and 42. These contacts on separating deenergize the actuating coil A 128 of the potential switch and the potential switch drops out to 110 break the circuit for the motor armature and field windings and to cause the application of the brake 7. The turning of lever 25 also causes the frame 81, pivotally carried thereby, to move downwardly, carrying with it the wedges 73 and 78. These wedges slide inwardly along the inclined faces 91 and 95 of the wedges 92 and 96 respectively. Continued downward movement of the lever 25 will cause the vertical grooves in the oppos- 115 120 125 130

ing faces of the clamps 69 and 80 carried by the wedges 73 and 78 to contact with and grip the hoisting ropes 3. The hoisting ropes, owing to their kinetic energy at this time, 5 are passing down through the rope clamp and hence assist in the continued downward movement of the wedges 73 and 78. Farther downward movement of the wedges 73 and 78 is accomplished by compressing the springs 10 93 and 97. These springs thus yield causing the hoisting ropes to be gripped between the clamps 69 and 80 with a force increasing in magnitude as wedges 73 and 78 move downward within the housing 28. Should the 15 wedges 73 and 78 move to the extent of engaging the bottom of the housing, 28, no further deflection of the springs 93 and 97 can take place and the gripping force of the clamps 69 and 80 upon the hoisting ropes 20 thereafter is constant depending upon the strength of the springs.

The kinetic energy of the portion of the hoisting ropes extending downwardly from the rope clamp 26 to the counterweight is 25 thus dissipated and these ropes are brought to rest. In the event that the counterweight has not been brought to rest by the buffer 12, or by engagement with the bottom of the hatchway as in the case where a buffer is not 30 employed, the kinetic energy of the counterweight is likewise caused to be dissipated. With the rope clamp 26 carrying the pull of that portion of the hoisting ropes extending below this clamp, the pull of this portion of 35 the ropes on the drum 4 and on the car ceases. The car 1 being relieved of this pull will come to rest with gravity retardation and without causing any shock to the elevator apparatus or to the passengers.

40 In a traction type elevator as illustrated in Figure 1, should the potential switch fail to drop out for any reason so that the motor 5 continues to operate, the tractive effort of the drum 4 upon the hoisting ropes leading 45 to the car is reduced to a negligible quantity and the hoisting drum slides with respect to these ropes, so that the continued rotation of the motor does not tend to raise the car.

As has been previously indicated, wedges 50 73 and 78 are connected by yokes to the mid-point of the cross-bars constituting a part of the frame 81. Since the cross-bars are carried by the ends of the equalizing-bars, at 55 equal distances from the pivotal supports of the equalizing-bars, it follows that the wedges 73 and 78 are connected to the frame 81 at equal distances from such pivotal supports. The downward force applied to one of these 60 wedges is therefore always equal to the downward force applied to the other. One wedge may move downwardly at a different rate of speed from that of the other, caused as by a difference in strength of the compression springs 93 and 97. Nevertheless, owing to 65 the equalizing of the forces acting upon the

wedges, they move in a vertical path and do not deflect the hoisting ropes. Inasmuch as the clamps 69 and 80 are free to swivel within the wedges 73 and 78 these clamps apply equal retarding forces to the separate hoisting ropes. By adjusting the nuts 157, 158 and 160, 161 the springs 93 and 97 may be placed under no initial compression or under any initial compression that may be desired, depending upon the requirements of the particular installation. An initial vertical adjustment of the wedges 73 and 78 may be obtained by turning studs 71 and 77 with respect to the wedges. The maximum retarding force that may be applied by the rope clamp to the hoisting ropes will depend upon the strength of the springs 93 and 97. This maximum force exists when the wedges 73 and 78 rest upon the bottom of the rope clamp 75 80 85 housing 28. By choosing springs of appropriate strength any desired retarding force may be obtained.

To operate the elevator car in the down direction the operator positions the car switch so that its contact segment 134 bridges contacts 164 and 148. The actuating coil C 165 of the down direction switch being energized, contacts C 141 and C 151 are separated and contacts C 166, C 167 and C 168 are engaged. Current now flows through the motor armature in a direction reversed to that described above and the car descends.

Under certain conditions of operation such as those analogous to the conditions enumerated for causing the car to run past the landing 100 129, the car may continue past landing 59 to such an extent that cam 98 strikes the roller 102 carried by the lever 100. Should the car continue in its course a predetermined extent, the lever 100 will release lever 105 in 105 the same manner that lever 14 released lever 20. Rope clamp 113 will thus operate in the same manner that rope clamp 26 operated, causing the separation of the pairs of cooperating contacts 115 and 116, the dropping 110 out of the potential switch, the breaking of the current to the motor armature and field windings and the application of the brake as before. The car will be brought to rest by the buffer 11. That portion of the hoisting 115 ropes extending between the rope clamp 113 and the elevator car will be retarded and finally supported by the rope clamp. The counterweight thus relieved of the pull due to the hoisting ropes will come to rest with 120 gravity retardation and without striking the upper limit of the hatchway.

The safety appliances may be reset manually. For example, if the safety appliance actuated by cam 13 has operated, it may be 125 reset by raising the rope clamp lever 25. Initial movement of this lever causes the clamps 69 and 80 to release the hoisting ropes. Further movement of the lever 25 causes the re-engagement of the pairs of cooperating con- 130

facts 41 and 42. The system may now be started in operation to cause the disengagement of the counterweight cam 13 from the roller 15 of the lever 14. Thereupon the lever 14 may be swung so that its catch 16 again engages the abutment 17 on lever 20 thus completing the resetting operation.

For convenience of illustration the rope clamps are shown for operating upon two hoisting ropes but it is to be understood that they are equally as well adapted for operation upon any number of hoisting ropes. For example when four hoisting ropes are employed, certain portions, such as the 10 wedges and springs, of each rope clamp, are duplicated for the two additional ropes. In such case the dimensions of the housing, frame, and weighted lever for each rope clamp are made such as to accommodate the 15 duplicate structure.

The safety appliance actuated by cam 13 on the counterweight may as readily be actuated by a cam on the car as it approaches the upper limit of the hatchway by merely 20 placing the roller 15 and connected mechanism in the path of travel of the cam carried by the car. Likewise the safety appliance actuated by cam 98 on the car may be actuated by a cam on the counterweight. Such 25 an arrangement is illustrated in Figure 6.

As many changes could be made in the above construction and many apparently 30 widely different embodiments of this invention could be made without departing from the scope thereof, it is intended that all matter contained in the above description or 35 shown in the accompanying drawings shall be interpreted as illustrative and not in a limiting sense.

What is claimed is:

1. An elevator system comprising, a car and a counterweight in the hatchway, a driving sheave, hoisting ropes connected to the car and counterweight and passing over said 45 driving sheave, and means, operated by the counterweight, for acting upon the hoisting ropes to cause the stopping of the car in its downward travel with substantially gravity retardation.

2. An elevator system comprising, two movable bodies in the hatchway, hoisting ropes connecting said movable bodies, means for stopping the descending body, means for gripping the hoisting ropes, and means actuated by the descending body as it comes to rest for causing the application of the gripping means.

3. An elevator system comprising, two movable bodies in the hatchway, a plurality of hoisting ropes connecting said movable bodies, and a safety appliance mounted in the hatchway comprising means for gripping all of said hoisting ropes with equal pressures, and means for normally retaining said gripping means in its inoperative position, said re-

taining means being arranged to be actuated by one of the movable bodies to cause the application of the gripping means.

4. An elevator system comprising, two oppositely movable bodies in the hatchway, 70 hoisting ropes connecting said movable bodies, and a safety appliance comprising a hoisting rope gripping means mounted near the top of the hatchway and a connected releasing mechanism mounted in the hatchway, said 75 releasing mechanism being adapted to be operated by the descending body as it comes to rest to cause the operation of the hoisting rope gripping means.

5. An elevator system comprising, two oppositely movable bodies in the hatchway, 80 hoisting ropes connecting said movable bodies, a buffer engaged to stop the descending body as it reaches its lower limit of travel, a cam mounted on said descending body, a rope clamp mounted near the top of the hatchway and comprising a housing with cooperating wedges therein and actuating means for causing said wedges to grip the hoisting ropes above the descending body, releasing means 90 connected with said actuating means and comprising a device in the path of travel of said cam, said cam striking said device, upon the stopping of the descending body, and causing the releasing means to release the 95 actuating means, and effect the operation of the rope clamp.

6. In an elevator system, an elevator car, a counterweight for the car, hoisting ropes connecting the car and counterweight, a motor 100 for raising and lowering the car and counterweight, a brake for the motor, a buffer for the car, a buffer for the counterweight, a safety appliance for gripping the hoisting ropes supporting the counterweight and for causing the deenergization of the motor and the application of the brake to stop the motor, said counterweight causing the operation of said safety appliance in the event that its buffer is compressed a predetermined amount, 110 and an additional safety appliance for gripping the hoisting ropes supporting the car and for causing the deenergization of the motor and the application of the brake to stop the motor, said car causing the operation of said additional safety appliance in the event that its buffer is compressed a predetermined amount. 115

7. In an elevator system, a movable body in the hatchway, a hoisting drum positioned in the upper portion of the hatchway, hoisting ropes extending from said hoisting drum to said movable body, and means mounted in the hatchway near the hoisting drum for gripping the hoisting ropes said means being operable by said body as it descends. 120

8. In an elevator installation, the combination of a drum, means to rotate the drum, a cable passing over the drum, a load connected to the cable on each side of the drum, the 130

weight of said cable and load normally causing a frictional engagement between the cable and drum sufficient to drive the cable in either direction that the drum rotates, and means
5 actuated by a downwardly traveling part of the device, as a load approaches its lower limit of travel, to render the drum drive ineffective, even though the weight of the long reach of cables is sufficient to normally cause
10 traction enough to continue the drive.

9. In an elevator installation, the combination of a drum, means to rotate the drum, a cable passing over the drum and having a reach depending at each side thereof, a load
15 connected to each reach, the engagement between the drum and cable being so constructed that the latter will be frictionally driven when the weight supported at one side of the drum differs from the weight supported at
20 the other side thereof by less than a predetermined ratio, and means actuated by either load, as it approaches its lower limit of travel, to render the drive ineffective by disturbing said ratio.

25 10. In an elevator installation, the combination of a drum, means to rotate the drum, cables passing over the drum and provided at each end with a load, gripping means located above the normal limit of elevator travel, a
30 tripping device near the lower limit of elevator travel and engageable by one of the loads as it approaches its lower limit of travel, and means connected to the tripping device for causing said gripping means to grip the cables
35 when the tripping device is so engaged.

In testimony whereof, I have signed my name to this specification.

FREDERICK HYMANS.
